ROUTE BOOK

Filed Feb. 19, 1923

2 Sheets-Sheet 2

INSTRUCTIONS

1. Enter month on title page, also the Company name and address.
2. Drivers name enter on title page.
3. Enter customers names and addresses in the wide columns between the heavy lines and in succession as they are served on the route.
4. Carry all balances from the previous month to the top spaces in the balance column.
5. Enter quantity or daily order in the lower spaces in the balance column.
6. Each day, in the date columns, in the top spaces enter the balance from the previous day plus the amount of purchase for that day.
7. Enter credits in the lower spaces of the date columns and carry the balances if any to the top spaces in the next column plus the purchase for that day.
8. Enter the date customers agree to pay account in last column.

UNITED STATES PATENT OFFICE.

ELMER E. FOREMAN, OF COLUMBUS, OHIO.

ROUTE BOOK.

Application filed February 19, 1923. Serial No. 619,918.

To all whom it may concern:

Be it known that I, ELMER E. FOREMAN, a citizen of the United States, residing at Columbus, in the county of Franklin and 5 State of Ohio, have invented certain new and useful Improvements in Route Books, of which the following is a specification.

This invention relates to that class of route books, which are especially adapted 10 for use by dairymen who daily deliver stated quantities of milk to their customers, and has for its particular objects to provide a book wherein a correct record of the accounts of the customers can be kept from 15 day to day, also a list of the customers' names and addresses in the consecutive order in which the daily deliveries are made, the notation of the quantity desired by each customer each day, and also a notice when 20 each customer desires to pay his individual account. Other objects of the improved route book is to provide an identification page, which if the book should be lost, will inform the finder to whom the book belongs, also a page of instructions of how to 25 use the book, which will enable a new employee to easily familiarize himself with the manner of keeping the accounts, and also enable a substitute to take over another 30 man's route should the demand arise without any serious inconvenience to the employers.

These objects are attained by the means 35 illustrated in the accompanying drawing, in which:—

Figure 1 is a plan view of an upper portion of one of the improved books in an open position.

Figure 2 is an edge view of the same. 40 Figure 3 is a view of a detached instruction leaf, and

Figure 4 is a similar view of the identification leaf.

Similar reference numerals in all figures 45 of the drawing designate like parts.

In its simplest form, the book comprises a series of leaves 10 of equal width, each leaf being ruled on its rear side a wide name column 11 and a series of narrow 50 columns, the first one of which has at its top end the abbreviation "Bal." designating that column as the balance column 12, and the remaining of said narrow column having numerals 1, 2, 3 etc. in consecutive 55 order designating said columns as date-columns. The front face of each leaf 10

is also ruled to form a series of narrow columns having numerals up to and including 31 in consecutive order and in continuation of the numerals on the rear face of the 60 adjacent leaf, and an edge column 12' designated a pay-time column follows the date columns for a purpose hereinafter set forth. The leaves are ruled on both sides with 65 a series of heavy horizontal lines 13 between which are formed a series of relatively wide spaces 14 that may be termed individual account spaces and these spaces are in continuation from the rear side of one leaf or page to and across the front 70 side of the adjacent leaf or page. These individual account spaces are divided by horizontal lines 15 which form upper and lower spaces in each individual account space, the upper spaces, which may be 75 termed debit-spaces, being used to record therein each day the amount due, and the lower spaces, which may be termed credit-spaces, being used to record the amount paid 80 any time during the month. Lines 15 are preferably fine lines as distinguished from the lines 13, or they might be of a different color from said lines 13, or be ruled in any manner to show a contrast, but it is understood 85 that the lines forming the individual account spaces must be prominent, so that a user of the book will be able to follow a single account entirely across the pages.

To avoid making the book too wide, narrow intermediate lines 16 are mounted 90 between the wide leaves 10, and these intermediate leaves are ruled on both sides similar to the other leaves to form the date-columns and individual account spaces in 95 continuation with other rulings or markings. These intermediate leaves have preferably ruled thereon seven date columns and are sufficiently wide to extend only to the name-columns, so when each one is folded back against the preceding page, it will 100 not cover any portion of the name-column thereon.

It will be observed that the date columns of the 7th, 14th, 21st and 28th days of the month are positioned as the first columns 105 on that side of the intermediate leaves, also the first column on the last page of the account and the first column exposed beyond the edge of the intermediate leaf respectively on said last page. Thus the total 110 amount due for a weekly account from the first day of the month will always appear

in one of the columns beginning a section of the account.

The wide leaves only are numbered preferably on the front sides and in their right-hand upper corners, thus dividing the book into a series of account-sections, each of which include the rear face of one main leaf, both sides of the intermediate leaf and the front face of the next main leaf.

- 10 A title page 17 is preferably provided and which on one side is provided with spaces to place the name of the month the book is to be used, the name and address of the owner of the book, the name of the delivery-man and his route number. Preferably on the opposite side of said title page are printed a list of instructions of how to use the book, so that a newly employed delivery-man, or a substitute can take up the route and manage 20 the same without any trouble or coaching.

Several instances of accounts are shown inscribed on the drawings, each of which is different from the others. The first account to Mrs. John Smith, is a daily pint account 25 as indicated by the word "Pint" placed in the lower space of the balance column, and it will be observed that the amounts due gradually increase the price of one pint from day to day, until the thirty-first day of 30 the month when it amounts to one dollar and eighty-eight cents. The pay time is indicated in the pay-time column as the "Last day of month", and it is shown that the account was paid in full on the last day by 35 the credit \$1.88 in the lower space of the thirty-first day of this account.

In the case of the account of A. R. Pratt, which is indicated as a quart daily delivery, the pay-time is indicated as the "First day 40 of the month". In this instance the amount due on the thirty-first day is transferred to the upper spaces of the balance column in the next month's account.

The next account inscribed, that of R. S. 45 Thompson, is a weekly account, and it will be observed the account is settled every seventh day from the first day of the month, the credit being marked in the lower or credit spaces and starting each eighth day 50 with a new account in the upper spaces. The account of L. A. Lang is an optional

payment account, wherein it will be seen the credits are credited in the lower spaces of the fourth, tenth and twenty-ninth columns, and the balances and the amount of the 55 daily supply are debited in the upper spaces of the next column. Thus on the fourth day of the month was paid fifty cents of a seventy-eight cent account, and the balance twenty-eight cents and the daily amount six 60 cents, making thirty-four cents, is carried to the upper space of the next column.

Having thus fully described my invention, what is claimed is:—

An account book comprising a series of 65 wide leaves and a relatively narrow leaf inserted between each pair of said wide leaves, the adjacent face of said wide leaves and both faces of said narrow leaf being 70 ruled with a plurality of vertical columns including a relatively wide name column at the free vertical edge of one of the wide leaves, a plurality of narrow date columns 75 on both sides of the narrow leaf and also on both wide leaves, a balance column between said name column and the first one of said date columns, and a pay-time column at the free vertical edge of the opposite wide leaf, all of said columns being appropriately 80 designated at the top edges of the pages which are also divided by horizontal lines to form individual account spaces extending continuously across the rear face of one of 85 said wide leaves and across both faces of said narrow leaf and also across the front face of the next wide leaf, said individual account spaces being subdivided with contrasting 90 lines to form equal size upper and equal size lower spaces throughout the length of the wide columns, and said narrow leaf being sufficiently wide only to extend to the inner end of the name column when folded back against the name column page, and also each side of the narrow leaf is arranged 95 with only sufficient date columns to record an account of one week, so that a weekly debit account can be easily ascertained by glancing at one of the end date columns on the pages.

In testimony whereof I affix my signature.

ELMER E. FOREMAN.
